ABSTRACT: The invention relates to a latch for a two-lid egg carton. The latch comprises a flap which extends from one lid across the other lid and cooperating latching means provided on the flap and on the other lid. The cooperating latching can be: A hole provided in the flap and a projecting button on the other lid which extends through the flap hole or a pair of ears are provided on the flap which are wedged into a corresponding recess on the other lid or are snapped into an opening provided on the other lid. The ears, recess or opening latching means can be used as a supplementary latching means in combination with the button and hole or can be used as the sole latching means.

POSITIVE LATCH FOR TWO-LID EGG CARTONS

DESCRIPTION

There has been a search for a good latch for a two-lid carton. U.S. Pat. Nos. 3,191,844 and 3,362,606 each show a friction latch which provides for a wall of each lid to be wedged between slots in posts and relying upon friction holding the lids in closed position. This type latch has proven to be commercially unsatisfactory since the amount of latching is inadequate. A tab and slot latch is proposed in U.S. Pat. No. 2,423,756. However, the construction of this patent has its drawbacks since the tabs 24 must be of stiff material to keep from curling under when the tabs strike the eggs during closing. Furthermore, as can be seen from the length of the tab 24 in FIG. 7 interference by the eggs during closing is a tremendous problem. Also, the tabs 24 can be wedged out of the position shown in FIG. 1 during nesting or stacking resulting in the misalignment between the tabs and slots 25 which is a serious problem when sent through an automated closure.

Accordingly, it is an object of this invention to provide a two-lid egg carton with a positive mechanical latch.

It is a particular object to provide a positive mechanical latch for egg cartons made from materials of various stiffnesses as for instance, foam plastic egg cartons, molded pulp egg cartons and solid plastic egg cartons.

Other objects of the invention will become apparent from the following description with reference to the drawing wherein:

FIG. 1 is a perspective view of an egg carton illustrating one embodiment of the invention;

FIG. 2 is a section view along section line 2-2 of FIG. 1;

FIG. 3 is an isolated top view of a flap shown in FIGS. 1 and 2;

FIG. 4 is an isolated top view of a button and surrounding recess shown in FIGS. 1 and 2;

FIG. 5 is a section view along section line 5-5 of FIG. 1;

FIG. 6 is a partial section view similar to FIG. 2 illustrating a modification of the embodiment of FIG. 1;

FIG. 7 is a partial top view illustrating another modification of the embodiment of FIG. 1;

FIG. 8 is a partial top view illustrating another modification of the embodiment of FIG. 1;

FIG. 9 is a view of an egg carton illustrating another embodiment of the invention;

FIG. 10 is a view of an egg carton illustrating another embodiment of the invention;

FIG. 11 is a top view of a flap illustrated in FIG. 10; and

FIG. 12 is a section view along section line 12-12 of FIG. 10.

Referring to FIGS. 1-5, there is illustrated an egg carton comprising an egg tray bottom 12 and a pair of lids 14 and 16 each pivotally connected tot to the tray at longitudinally extending hinge lines 18 and 20, respectively. The lid 14 comprises a sidewall 22 extending from the hinge line 18 and transversely to a planar top wall 24 and the planar wall 24 extends to a sidewall 26 at the free end of the lid which lies in a plane transverse to the planar wall 24. The lid 16 comprises a sidewall 28 extending from the hinge line 20 and transversely to a planar top wall 30 and the planar wall 30 extends to a sidewall 32 at the free end of the lid which lies in a plane transverse to the wall 30. Each lid can best be described as cup or U-shaped in cross section of as illustrated in FIG. 2 a locking flap 34 is pivotally connected at hinge line 36 to the lid 14 and has a pair of ears 38 and 40 at the free end thereof and an opening 42 therein. In the latched position, a button projection 44 extends upwardly from a flap receiving recess 46 in planar wall 30 through the opening 42 of the flap and the recess 46 located on the wall 30 receives the flap 34 therein. A depression 48 is provided in the lid 16 to provide access for ones finger to disengage the flap 34. When the lids 14 and 16 are in closed position as shown in FIG. 2 the sides 26 and 32 engage each other with the free end edge 50 and 52, respectively, bearing on a center post 54. The cells and post structure of the egg tray 12 may be constructed in any well-known

manner, for instance, as shown in any of the U.S. Pat. Nos. 3,191,844; 3,362,606 or 2,446,264.

The flap 34 is cut out of the sidewall 26 and is the same length as the vertical length figure (figure 2) of the wall 26. The hinge line 36 is provided at the upper portion of the wall 26 at the juncture of walls 24 and 26 whereby the flap is pivoted about the hinge line 36 for into a latching position or beyond. When the flap is pivoted beyond the plane of top wall 24, the resilient nature of the hinge 35 36 is such that the flap will tend to pivot back towards the wall 26. This resilient nature of the hinge 36 helps maintain the button 44 in the opening 42 when the flap 34 is in latched position.

Ears 38 and 40 are provided on the flap 34 and corresponding ear receiving recesses 56 and 58 are provided in the flap receiving recess 46 to provide additional latching assurance. Referring in particular to FIGS. 3 and 4, the flap receiving recess 46 on the top wall 30 of cover 16 is of essentially the same shape as the flap 34 and comprises a top wall 47 offset or depressed from the main plane of the top wall 30 a distance slightly greater than the thickness of flap 34. However, the distance *d* between the ends of the ear receiving recess portions 56 and 58 is less than the distance *D* between the ends of the ears 38 and 40 so that the free end of the latch 34 will have to be wedged into the corresponding end portion of the recess as shown in FIG. 5 and the ends of the ears 38 and 40 will each frictionally grip the corresponding sidewalls or shoulders 60, 68, 62 and 70 of the recess portions 56 and 58, respectively. The shape of the ears is not important as long as the ears project from the flap.

If the lids 14 and 16 are squeezed in the direction of arrows A-B (FIG. 2), the edge 64 and 66 of the ears engage corresponding edges 68 and 70 of the ear receiving recesses 56 and 58, respectively, to hold the free end of the flap in place to assure return of the flap 34 to its latched position should the flap and button become disengaged. The flap will buckle tending to raise the flap relative to the button 44 and if the flap disengages from the button 44, the flap will return back to its prior latching condition with the button upon release of the squeezing pressure since the free end of the flap has remained in place. As soon as the squeezing pressure is released, the flap will regain its prior latched position. If there is any lateral "racking" action of the lids in simultaneous opposite direction as shown by arrows C-D (FIG. 1), the edge 76 of the flap and edge 78 of the recess will engage to prevent any significant relative lateral movement between the lids. If the "racking" action is in the opposite direction of the arrows C-D, then the edges 72 and 74 will cooperate to prevent any significant relative movement between the lids.

The dimensions between the opening 42, button 44, edges 80 and 82 of the flap 34 and shoulders 60 and 62 of the recess 46 are such that any tension imposed on the flap 34 by forces tending to open the lids will be shared by the edges 80 and 82 of the ears 38 and 40, respectively, bearing on shoulders 60 and 62, respectively, and the edge of opening 42 bearing on the button 44. Depending upon tolerances, the edge of opening 42 may deform slightly under load before a force will be applied to the ears 38 and 40 or vice versa. It should be realized that upon any tendency of the lids to open, the lids pivot away from each other and therefore the flap 34 and surface 30 tend to move in opposite directions with the button 44 and recess walls 60, 62 placing the flap 34 in tension. Therefore even if the carton is turned upside down, the weight of the eggs will tend to open the lids 14 and 16 but at the same time place flap 34 in tension whereby the flap is held in latched position.

An additional, but not necessary, method for maintaining the flap 34 is latched in latched position is to place the flap in tension while in latched position. This can be accomplished by bowing the walls 26 and 32 in opposite directions whereby when the lids are in the position of FIG. 2, and a tray such as that shown in U.S. Pat. No. 2,446,264 is used, the lids will be biased away from each other placing the flap in tension.

Referring to FIG. 6 a modification of FIG. 1 is shown. The same reference numerals are utilized to designate the same elements in FIG. 1-5 only an *a* is affixed thereto. An undercut 102 is provided in the button 44*a* and the opening 42*a* is located on the flap 34*a* so the portion 104 of the opening 42*a* fits into the undercut 102. The undercut provides an additional feature against accidental unlatching due to squeezing, racking or any other force tending to lift the flap 34*a* away from latching position. An alternative to the undercut is to "back draft" or slant the surface of the post engaging edge 104 from the top of the button 44*a* to the recess 46 in a direction away from the free end of the lid or the whole button may be slanted in the same direction.

Referring to FIG. 7, there is illustrated another modification of FIG. 1. The same reference numerals are utilized to designate the same elements in FIGS. 1-5 only a *b* is affixed thereto. In this embodiment, the ears are left off and the latch is provided by the button 44*b* and opening 42*b* in the flap. The edges 72*b*, 74*b*, 76*b*, and 78*b* cooperate to minimize "racking." Obviously, the edge of the opening 42*b* will have to be located immediately adjacent or contiguous the button 44*b* in order that tension will be almost immediately applied to the flap upon any opening force being applied to the lids. Furthermore, if desired, the walls corresponding to walls 26 and 32 in FIG. 2 can be bowed as described above to place the flap in tension during latched position.

Also, if desired, the opening 42*b* may be necked or in the form of an ellipse with the dimension of the necked portion or the smallest dimension of the ellipse being slightly smaller than the corresponding dimension of the button 44*b*. In this case, the shortest radius of the ellipse or the dimension of the neck portion will extend in the longitudinal direction. The edge of the opening at the smallest dimension will frictionally grip the button 44*b* to resist disengagement of the flap from the button in case of a squeezing action being applied to the lids. Also, the undercut disclosed in FIG. 6 or a slanted post can be utilized in this embodiment.

Referring to FIG. 8, there is illustrated another embodiment of FIG. 1. The same reference numerals are utilized to designate the same elements in FIGS. 1-5 only a *c* is affixed thereto. The button and opening therefor has been eliminated. The ears and ear receiving recess perform the sole latching function with edges 80*c*, 60*c*, 82*c*, and 62*c*, taking any force tending to open the lids.

The stiffness of foam plastic varies. If foam of high stiffness or molded pulp or a solid plastic is used wedging of the ears 38*c* and 40*c* into the ear receiving recess is more effective. However, if a stiff material is used, the dimensions *D* and *d*, as shown in FIGS. 3 and 4, can be approximately the same whereby the ears 38*c* and 40*c* are not wedged into the ear receiving recesses. The stiff material will perform almost as well as if the ears were wedged which is more or less required with relatively soft material. Obviously, a stiff material can be used in any of the preceding embodiments of FIGS. 1, 6, and 8.

FIG. 9 is another embodiment of FIG. 1. The same reference numerals are utilized to designate the same elements in FIGS. 1-5 only a *e* is affixed thereto. The button and opening therefor has been eliminated. An opening 202 is provided through which the flexible free end of the flap 34*d* is tucked whereby the ears 38*d* and 40*d* snap past the edge of opening 202 to become lodged under the wall 30*d* to prevent the flap from being dislodged from latching position. The ears 38*d* and 40*d* bear on the edge 204 of the opening to take any force tending to open the lids. Obviously, openings could be provided just for the ears 38*d* and 40*d* with the opening 202 closed in the same manner as surface 48 in FIG. 1.

Referring to FIGS. 10-12, another modification is illustrated. The same reference numerals are utilized to designate the same elements in FIGS. 1-5 only an *e* is affixed thereto. A strap or flap 302 is secured to the top wall 24*e* by any suitable means such as an adhesive or, as shown, by a pair of staples 304. The flap may be made out of any flexible material such as

polypropylene. The flap comprises a neck portion 306 and a pair of ears 308 and 310 at the free end thereof. An opening 312 is punched in the wall 28*e*. The tab portion 314 of the wall which was punched out to provide the opening 312 is left attached at the hinge line 20*e* for aesthetic purposes and keeping the inside of the carton clean.

The width between the ends of the ears 308 and 310 is greater than the corresponding width of the opening 312 and the width of portion of opening 312 corresponding to a the neck 306 is approximately the same as the width of the neck portion 306. In closing the carton, the flap is placed on top of the wall 30*e* and is bent downwardly at the neck portion 306 and since the flap 302 is flexible, the flexible ears 308 and 310 snap past the edge of the opening 312 to assume a latched position. Any force tending to open the lids will be resisted by the edge of the ears 308 and 310 at the neck portion 306 bearing on the corresponding edge portion of the opening 312.

I claim:

- 20 1. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising an opening therein; latching means carried by said other lid surface means comprising a button projecting upwardly therefrom and extending through said opening when said flap is in latched position to hold said lids in closed position whereby the edge of said opening and said button will coact to resist opening of said lids when said flap is in latched position and said flap is placed in tension when an opening force is applied to said lids.
- 25 20 2. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising an opening therein; latching means carried by said other lid surface means comprising a button projecting upwardly therefrom and extending through said opening when said flap is in latched position to hold said lids in closed position whereby the edge of said opening and said button will coact to resist opening of said lids when said flap is in latched position and said flap is placed in tension when an opening force is applied to said lids.
- 30 25 3. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 35 30 4. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 40 35 5. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 45 40 6. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 50 45 7. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 55 50 8. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 60 55 9. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 65 60 10. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 70 65 11. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.
- 75 70 12. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; latching means carried by said latching flap comprising at least one ear extending in a longitudinal direction therefrom; latching means carried by said other lid surface means comprising at least a recessed portion conforming in shape to said at least one ear and the corresponding portion of said flap from which the ear extends; said ear and corresponding portion of said flap from which the ear extends being received in said recessed portion when the flap is in latched position whereby said ear and its corresponding portion of said recessed portion con coacts to resist opening of said lids and said flap is placed in tension when an opening force is applied to said lids.

carried by said flap comprising at least one ear extending in a longitudinal direction therefrom; latching means carried by said other lid surface means comprising an opening; said opening, the ear and the portion of said flap from which the ear extends being so proportioned and arranged that when the flap is in latched position, the ear will extend in the opening beyond the boundary of the opening under the surface means of said other lid and coact with the edge of the opening to resist opening of said lids whereby said flap is placed in tension when an opening force is applied to said lids.

4. An egg carton comprising: An egg receiving bottom tray comprising a pair of spaced longitudinally extending sidewalls; a pair of lids each comprising outer surface means terminating at an inner longitudinal edge and a free longitudinal edge; each lid being pivotally connected at its said inner longitudinal edge to a respective one of said sidewalls whereby the lids can pivot in a direction toward each other into a closed position covering said tray; a latching flap pivotally connected to one of said lids and when the lids are in said closed position extends in a direction transverse to the longitudinal edges and a substantial portion thereof engages said outer surface means of the other of said lids; and latching means carried by said latching flap and latching means carried by said other lid surface means cooperating with said latching flap means when said flap is in latched position to hold said lids in closed position; said cooperating latching means being so constructed and arranged relative to each other to provide a positive mechanical interlock when said flap is in latched position whereby said flap is placed in tension when an opening force is applied to said lids; said other lid having a recess in said surface means thereof receiving the entire flap therein when said flap is in latched position; said recess including a pair of longitudinally spaced walls; said longitudinally spaced walls and the corresponding edges of said flap being closely adjacent each other to resist substantial relative longitudinal movement between said lids.

5. The structure as recited in claim 1 wherein there is an undercut in the portion of said button which coacts with the edge of said opening to resist opening of said lids; at least a portion of the edge of said opening of said lids; at least a portion of the edge of said opening is disposed in said undercut when the flap is in latched position.

6. The structure as recited in claim 2 wherein a pair of ears are provided which extend in opposite longitudinal directions from opposite sides of the free end of said recessed portion.

7. The structure as recited in claim 1 wherein said latching means carried by said flap further comprises at least one ear extending in a longitudinal direction therefrom and said latching means carried by said other lid surface means further comprises an opening; said opening, the ear and the portion of said flap from which the ear extends being so proportioned that when the flap is in latched position, the ear will extend in the opening beyond the boundary of the opening under the surface means of said other lid and coact with the edge of the opening to additionally resist opening of said lids and to prevent the edge of said flap opening and said button from being dislodged from a latching position.

8. The structure as recited in claim 7 wherein said surface means of each lid comprises a first sidewall, one longitudinal edge of which is said inner edge pivotally connected to the sidewall of said tray; a second sidewall one edge of which is said free edge; and a planar top wall the longitudinal edges of which join the other longitudinal edges of said lid sidewalls; said opening carried by the other lid surface means being on the planar top wall thereof.

9. The structure as recited in claim 8 wherein the pivotal connection of said flap to said one lid is generally at the juncture of said second sidewall and said planar top wall.

10. The structure as recited in claim 3 wherein said surface means of each lid comprises a first sidewall, one longitudinal edge of which is said inner edge pivotally connected to the sidewall of said tray; a second sidewall, one edge of which is said free edge; and a planar top wall the longitudinal edges of

which join the other longitudinal edges of said lid sidewalls; a said opening carried by the other lid surface means being on the first sidewall.

11. The structure as recited in claim 10 wherein said latching means carried by said flap comprises a pair of ears which extend in opposite longitudinal directions from opposite sides of the free end of said flap.

12. The structure as recited in claim 4 wherein said surface means of each lid comprises a first sidewall, one longitudinal edge of which is said inner edge pivotally connected to the sidewall of said tray; a second sidewall one edge of which is said free edge; and a planar top wall the longitudinal edges of which join the other longitudinal edges of said lid sidewalls; said latching means carried by the other lid surface means being on the planar top wall thereof, the pivotal connection of said flap to said one lid being generally at the juncture of said second sidewall and said planar top wall; and said other lid has said recess in said planar top wall thereof.

13. The structure as recited in claim 1 wherein said surface means of each lid comprises a first sidewall, one longitudinal edge of which is said inner edge pivotally connected to the sidewall of said tray; a second sidewall, one edge of which is said free edge and a planar top wall the longitudinal edges of which join the other longitudinal edges of said lid sidewalls; said latching means carried by the other lid surface means being on the planar top wall thereof; said pivotal connection of said flap to said one lid defining an integral connection between said flap and lid and being generally located at the juncture of said second sidewall and said planar top wall; an opening in said second sidewall of said one lid from which said flap is pivoted; said button is located on said top wall of said other lid; the portion of the surface of said button coacting with the edge of said opening is from the uppermost portion of the button toward the top wall of said one lid slanted in a direction toward said first lid.

14. The structure as recited in claim 1 wherein said surface means of each lid comprises a first sidewall, one longitudinal edge of which is said inner edge pivotally connected to the sidewall of said tray; a second sidewall, one edge of which is said free edge, and a planar top wall, the longitudinal edges of which join the other longitudinal edges of said lid sidewalls; said button being on the planar top wall of said other lid; the pivotal connection of said flap to said one lid being generally at the juncture of said second sidewall and said planar top wall.

15. The structure as recited in claim 14 wherein an opening is in said second sidewall of said one lid from which said flap is pivoted.

16. The structure as recited in claim 15 wherein said other lid has a recess in said planar top wall thereof receiving the entire flap therein; the walls of said recess and the corresponding edges of said flap being arranged to engage each other to resist substantial relative longitudinal movement between said lids.

17. The structure as recited in claim 1 wherein said latching means carried by said flap further comprises at least one ear extending in longitudinal direction therefrom and said latching means carried by said other lid surface means further comprises a recessed portion; said ear and corresponding portion of said flap from which the ear extends being received in said recessed portion when the flap is in latched position; said recess portion being so shaped that said ear and its corresponding portion of said recessed portion coacts to additionally resist opening of said lids.

18. The structure as recited in claim 17 wherein said surface means of each lid comprises a first sidewall, one longitudinal edge of which is said inner edge pivotally connected to the sidewall of said tray; a second sidewall, one edge of which is said free edge; and a planar top wall, the longitudinal edges of which join the other longitudinal edges of said lid sidewalls; said button and said recessed portion being on the planar top wall of said other lid; the pivotal connection of said flap to said one lid being generally at the juncture of said second sidewall and said planar top wall.

19. The structure as recited in claim 18 wherein an opening is in said second sidewall of said one lid from which said flap is pivoted.

20. The structure as recited in claim 18 wherein said recess receives the entire flap therein when said flap is in latched

position; said recess including a pair of longitudinally spaced walls; said longitudinally spaced walls and the corresponding edges of said flap being closely adjacent each other to resist substantial relative longitudinal movement between said lids.

UNITED STATES PATENT OFFICE
CERTIFICATE OF CORRECTION

Patent No. 3,556,387 Dated January 19, 1971

Inventor(s) David C. Trimble

It is certified that error appears in the above-identified patent and that said Letters Patent are hereby corrected as shown below:

✓

Column 1, line 53 omit " tot ".

Column 2, line 9 omit " 35 ".

Column 2, line 45 omit " ad ".

Column 2, line 70, " is latched latched " should read -- in latched --.

Column 3, line 60 " e " should read -- d --.

In the Claims

Claim 5, line 40 omit " sad ". Also in lines 40 and 41, omit " at least a portion of the edge of said opening of said lids; ".

Claim 6, line 46, insert between " said recessed ", the following -- flap and said ears are wedged into said --.

Claim 16, line 51 reference to " Claim 15 " should read -- Claim 14 --.

Signed and sealed this 11th day of May 1971.
